COMBINED VALET STAND AND SEAT

George J. Ritter, 32740 Whispering Palms Trail,
Palm Springs, Calif. 92262

Filed Feb. 4, 1971, Ser. No. 112,846

Term of patent 14 years

Int. Cl. D6—02

U.S. Cl. D6—33

FIG. 1 is a front perspective view of my combined valet stand and seat illustrating the new design.

FIG. 2 is a side elevation view of the dressing chair of FIG. 1.

FIG. 3 is a rear elevation view of the dressing chair of FIG. 1.

FIG. 4 is a top plan view of the dressing chair of FIG. 1.

I claim:

The ornamental design of a combined valet stand and seat as shown and described.
